(57) **CLAIM**

The ornamental design for a basketball hoop support as shown and described.

DESCRIPTION

FIG. 1 is a perspective view of a basketball hoop support showing the claimed design with environmental structure; FIG. 2 is a perspective view thereof; FIG. 3 is a right-side view thereof; FIG. 4 is a left-side view thereof; FIG. 5 is a back view thereof; FIG. 6 is a front view thereof; FIG. 7 is a top view thereof; and, FIG. 8 is a bottom view thereof.

Broken lines in the figures illustrate environmental structure and/or portions of the basketball hoop support that form no part of the claimed design. Specifically, environmental structure illustrated by dash-dot-dot broken lines in FIG. 1 forms no part of the claimed design, and portions of the basketball hoop support illustrated by dash-dot broken lines in FIGS. 1-8 form no part of the claimed design.
